UNITED STATES PATENT OFFICE

WALTER L. CHURCH, OF HOUSTON, TEXAS, ASSIGNOR OF ONE-HALF TO TEXAS IRON
WORKS SALES CORPORATION, OF HOUSTON, TEXAS, A CORPORATION OF TEXAS

SETTING TOOL

Application filed December 16, 1932. Serial No. 647,584.

This invention relates to a setting tool.

An object of the invention is to provide a setting tool whereby a conventional type of packer may be set in a well, and which 5 may be easily detached from the packer and removed from the well.

Another object of the invention is to provide novel means for connecting the setting tool to the packer support and which will 10 prevent the premature expansion of the packer while going into the well but which may be disconnected from the packer support without substantial injury to the connecting threads whereby the tool is connected 15 to the packer support.

With the above and other objects in view the invention has particular relation to certain novel features of construction, operation and arrangement of parts, an example 20 of which is given in this specification and illustrated in the accompanying drawings wherein:

Figure 1 shows a side view partly in section of the upper end of the setting tool.

Figure 2 shows a cross sectional view 25 taken on the line 2—2 of Figure 1.

Figure 3 shows a side view partly in section of the lower end of the tool shown connected to the packer support and showing also the packer.

Figure 4 shows a side view partly in section of the packer support and packer showing the latter set.

Figure 5 shows a side view partly in section 35 of the upper end of a slightly modified form of the tool.

Figure 6 shows a cross sectional view thereof.

Figure 7 shows a side elevation partly in 40 section of the lower end of said setting tool connected to the packing support, and

Figure 8 shows a side view partly in section of the modified form of setting tool and showing the packer set.

45 In completing a well it is common practice to set a screen or perforated pipe in the well opposite the producing stratum and to then set a packer between the upper end of the screen and the surrounding casing or 50 other walls of the well.

In the present illustration the numeral 1 designates the screen or other pipe to be set in the well and connected to and upstanding from this screen there is a tubular support 2. The upper end of this support has the 55 external downwardly pitched ratchet teeth 3. Around this support there is an expandible packer 4 of any conventional construction whose lower end may be secured to the support in any preferred manner, as shown 60 by the wire wrapping 5. Around the packer support above the packer there is a coupling 6 whose lower end is reduced and surrounded by the upper end of the packer 4 and said upper end of the packer is secured 65 to said coupling, in any manner preferred, as by the wire wrapping 7. The coupling 6 has the inside downwardly converging seat 8 on which is seated the wedge-shaped dog 9 whose inner side has the upwardly pitched 70 teeth 10 to engage the teeth 3.

There is the upstanding setting nipple 11 whose lower end is screwed on to the reduced upper end of the coupling 6 and whose upper end is preferably formed into 75 an outwardly flared seat 12.

The numeral 13 refers to an operating string of pipe which extends to the ground surface and through which the screen, packer and setting tool may be lowered and the 80 packer set and the tool then detached and withdrawn. Attached to the lower end of the string 13 is the enlarged coupling 14 whose lower end is provided with an inside 85 annular shoulder 15 and also with the inside vertical keyways 16 beneath said shoulder. There is a tubular connecting nipple 17 whose lower end is connected into the upper end of the packer support 2 by means of the left hand threads 18 and whose upper end 90 is extended up into the coupling 14 and has the enlarged head 19 which rests on the shoulder 15 and above which there is the packing assembly 20 consisting of the conventional upwardly opening cup ring and retaining gland commonly used. The connecting nipple 17 has the external longitudinal keys 21 whose upper ends are spaced beneath the head 19. The apparatus is assembled to be let down into the bore as 100

shown in Figures 1 and 3 with the lower end of the connecting nipple 17 screwed into the upper end of the body 2 and with the head 19 resting on the shoulders 15 and the lower 5 end of the coupling 14 above the upper ends of the keys 21 and with said keys out of alignment with the keyways 16 and the packer 4 collapsed. As so assembled and connected to the upper end of the screen 1, 10 said screen packer and setting tool may be let down into the well by means of the string 13 until the lower end of the screen rests on the bottom of the well. Thereupon the string 13 may be turned to carry the 15 keyways 16 into alignment with the keys 21 and the string and coupling 14 then further lowered and the lower end of said coupling will land upon the seat 12 of the setting nipple 11 forcing said setting nipple down- 20 wardly and expanding the packer 4 into close contact with the surrounding casing 22. The packer will be maintained in said expanded position by the dog 9 whose teeth will engage the teeth 3 to prevent the col- 25 lapsing of the packer. If desired the coupling 6 may have also the flexible upstanding arms 23 whose inner surfaces are toothed to engage the ratchet teeth 3 and to form additional means for holding the packer 30 expanded.

In the form shown in Figures 5 to 8 inclusive there is the enlarged coupling 14' connected to the lower end of the string 13 whose lower end is reduced in diameter and 35 provided with the tapering internal threads 24 and the vertical key ways 25 leading from said threads down to the lower end of said coupling 14'. In this form there is a connecting nipple 17' whose upper end is flared 40 and provided with the external threads 26 which may be screwed into the threads 24. The lower end of this nipple is screwed into the upper end of the packer support 2 by left hand threads and said nipple 17' has 45 the vertical keys 21 thereon. In other respects this form of setting tool is similar to that shown in Figures 1 to 4 inclusive. In assembly the nipple 17' is screwed into the packer support 2 and the threads 24, 26 con- 50 nected and the entire apparatus with the screen attached, then lowered into the well until the screen lands on the bottom of the bore. Thereupon the operating string 13 is turned to the right to unscrew the threads 55 24 from the threads 26 and the coupling 14' is then lowered and turned to align the keyways 25 with the keys 21 and then lowered to land on the setting nipple 11 which is moved downwardly to expand the packing 60 4 as hereinabove explained and said packer is maintained in an expanded position by the means hereinbefore described.

When the packer has been set the setting tool of either form may be released for 65 withdrawal by a further rotation of the op-

erating string 13 to the right whereupon the left hand threads 18 will be disconnected from the packer support and the operating string and setting tool then withdrawn. It is to be noted that while the threads 18 are 70 being unscrewed they will sustain only the weight of the connecting nipple 17 or 17', and not the weight of the entire operating string 13 and consequently said threads will sustain very little wear and will not be liable 75 to be injured and therein one of the chief advantages of this type of setting tool resides.

The drawings and description describe 80 what is now considered to be a preferred form of the invention by way of illustration only, while the broad principle of the invention will be defined by the appended claims.

What I claim is:

1. A packer setting tool comprising a coupling member adapted to be connected to an operating string, a connecting nipple whose upper end is telescoped into said coupling member and whose lower end is adapted to be connected to a packer support, means connecting said nipple to said coupling member and being releasable by the relative rotation of said coupling member to permit the descent of the coupling member relative to said nipple and means for locking said coupling member and nipple against relative rotation upon such descent. 95

2. A packer setting tool comprising a coupling, an operating string connected to said coupling, a connecting nipple, a support to which the lower end of the nipple is threaded, means connecting said nipple to said coupling and releasable upon the rotation of the coupling to permit said coupling to descend and means arranged to clutch the coupling with said nipple upon the descent of the former, whereby said nipple may be turned with the coupling and unscrewed from said support. 110

3. A packer setting tool comprising a coupling whose upper end is adapted to be connected to an operating string, a connecting nipple whose upper end is telescopically related to said coupling and whose lower end has left hand threads for connection to a packer support, means for connecting said coupling to said nipple said means being releasable upon the turning of said coupling member relative to said nipple whereby the coupling may descend and means for interconnecting the coupling and nipple for simultaneous rotation, upon such descent, whereby said nipple may be unscrewed from said support. 115

4. In a packing device having a packer support, an expansible packer thereon and a setting nipple arranged to actuate the packer; a setting tool comprising a coupling member adapted to be connected to an op- 130

erating string, a connecting nipple whose lower end is connected to said support, means for connecting the upper end of said connecting nipple to said coupling, said connecting means being formed to be released upon the rotation of said coupling to permit the coupling to descend onto said setting nipple whereby said packer may be expanded and means for connecting said coupling and connecting nipple for simultaneous rotation upon such descent.

means for interconnecting the coupling with said connecting member, upon such descent, whereby said connecting member may be rotated by said coupling to disconnect said threaded connection, said clutch means comprising a longitudinal key and keyway one on the connecting member and the other on the coupling arranged to intermesh upon such descent of the coupling. 70

In testimony whereof I have signed my name to this specification. 75

5. In a packing device having a packer support, an expansible packer thereon and a setting nipple arranged to actuate the packer; a setting tool comprising a coupling member adapted to be connected to an operating string, a connecting nipple whose lower end is threaded to said support, means for connecting the upper end of said connecting 15 nipple to said coupling, said connecting means being formed to be released upon the rotation of said coupling to permit the coupling to descend onto said setting nipple whereby said packer may be expanded and 20 means for connecting said coupling and connecting nipple for simultaneous rotation, upon such descent, whereby said connecting nipple may be unscrewed from said support. 25

6. In a packing device for wells and having a packing device for wells and having
30 a packer support, an expansible packer thereon and a setting nipple by means of which the packer may be expanded; a setting tool comprising a coupling adapted to be connected to an operating string, a tubular connecting member whose lower end has a threaded connection with the upper end of said support, means for connecting the upper end of said connecting member to said coupling to prevent the relative longitudinal movement of said coupling and connecting member, said means being releasable upon the rotation of said coupling to permit the coupling to descend onto said nipple to effect the expansion of the packer, clutch means
40 for interconnecting the coupling with said connecting member, upon such descent, whereby said connecting member may be rotated by said coupling to disconnect said threaded connection.

50 7. In a packing device for wells and having a packer support, an expansible packer thereon and a setting nipple by means of which the packer may be expanded; a setting tool comprising a coupling adapted to
55 be connected to an operating string, a tubular connecting member whose lower end has a threaded connection with the upper end of said support, means for connecting the upper end of said connecting member to said coupling to prevent the relative longitudinal movement of said coupling and connecting member, said means being releasable upon the rotation of said coupling to permit the coupling to descend onto said nipple to effect the expansion of the packer, clutch
